UNITED STATES PATENT OFFICE

OWEN R. TERRY, OF DETROIT, MICHIGAN

DEVICE FOR FILLING FOUNTAIN PENS

Application filed May 21, 1930. Serial No. 454,232.

My invention relates generally to fountain pen filling devices and more particularly to automatic means incorporated in an ink well whereby a fountain pen may easily be refilled without the necessity of operating the usual filling means provided in the pen. It is among the objects of my invention to provide an improved combination ink well and filling device: (1) which will operate automatically upon insertion of a fountain pen to fill or partially fill the barrel or reservoir thereof; (2) which will operate automatically upon insertion of a fountain pen to create a partial vacuum within the reservoir of the pen; (3) in which the partial vacuum created in the reservoir of the pen is relieved near the completion of the operating stroke; (4) by which a fountain pen may be filled without permitting any except the end surface of the pen section or barrel to come in contact with the ink; (5) which is operable by a single stroke, first, to exhaust air from the fountain pen reservoir and then permit filling the said reservoir by the in-flow of ink under atmospheric pressure; (6) in which an improved means for forming a seal with the end of the pen section or barrel is provided; (7) in which a novel arrangement of air vents is incorporated; (8) in which means are provided for returning to the ink well any ink which may leak past the piston stem; (9) which will not spill if accidentally tipped; (10) which will be efficient in cleaning fountain pens having clogged ducts; (11) which may easily be filled; (12) in which evaporation is reduced to a minimum; and (13) which has a minimum number of parts, is simple in construction, efficient in operation, may be economically manufactured, and (40) which will require the minimum of attention on the part of the user.

Other objects will appear from the following description, reference being had to the accompanying drawings, in which:

Fig. 1 is a central vertical sectional view of the device in normal position;

Fig. 2 is a view similar to Fig. 1 with the parts shown in operating position;

Fig. 3 is a transverse sectional view taken on the line 3-3 of Fig. 1; and

Fig. 4 is a fragmentary elevational view showing the check valve construction.

The device of my invention comprises a body 10 made of hard rubber, phenol condensation products, or any similar material, 55 which may easily be formed to the desired shape and which will not be corroded by the usual constituents of ink. The body has an axial cylinder bore 12 formed in the lower end thereof and a similar bore 14 formed in 60 the upper end thereof. The wall 16 between the ends of these bores has a central opening 18 and forms a guide for a stem 20, which is preferably formed integrally with a piston 22 reciprocable in the cylinder 12. The upper end of the stem 20 is tubular in shape so as to be adapted to receive a soft rubber obturator tube 24 which is shouldered at 26 to fit over the end of the stem 20 and is held in place by a ring 28 threaded over the end of 70 the stem and slidably fitting in the cylindrical bore 14.

The upper end of the obturator tube has a frusto-conical seating surface 30 which is adapted to engage and seal against the outer lower edge of the section or barrel of a fountain pen, as indicated in Fig. 2. The obturator tube is thus adapted to make an air tight connection with fountain pens having the ends of their sections of different diameters. A conical coil spring 32 has its lower end seated upon the cross-wall 16 and its upper end engaging beneath the ring 28. The stem 20 has a vertical passageway 34 communicating with the interior of the obturator tube 24, the lower end of the passageway 34 being connected to one or more substantially horizontal ducts 36.

The body 10, together with the parts mounted therein, may be inserted in any suitable ink well or container 38, the body having an enlarged diameter portion 40 fitting within a complementally shaped opening 46 in the ink well and having an outwardly extending bead 48 to limit the depth to which the body may be inserted in the ink well.

The body has one or more diagonal passageways 50 which are adapted to permit escape of air from the interior of the ink well upon depression of the stem, the upper end 100

of the passageway being uncovered as the ring 28 moves downwardly. One or a plurality of passageways 52 are provided in the upper portion of the body 10 to form breather ducts and thereby permit equalization of pressure between the ink well (and hence the atmosphere) and the space between the piston stem 20 and the walls of the cylindrical bore 14. The passageway or passageways 52 open into the lower end of the cylindrical bore 14 so that should any ink accidentally collect within this bore it will be ejected through the passageway 52 into the ink well upon downward movement of the ring 28 which thus acts as a piston.

Leakage of ink around the stem 20 is prevented or lessened by the provision of a plurality of annular grooves 54 formed in the bore 18. Similar annular grooves 56 are provided in the piston 22. These grooves, as well as the grooves 54, permit the collection of ink therein and thus form a liquid sealing means for the relatively moving parts. A plurality of radial ducts 58 are provided in the body 10 at the upper end of the cylindrical bore 12, the outer ends of these ducts being normally closed by flap check valves 60.

As best shown in Fig. 4, these check valves, which are preferably made of a comparatively soft rubber, have a rectangular portion 62 formed integrally with the substantially circular portion 64. The body 10 is formed to provide a seat for these check valves at the end of each of the ducts 58 by saw-cuts 35 taken at an angle to the axis of the body and substantially perpendicular to the axes of the ducts 58. A portion of the body which is thus partially severed by this saw-cut is cut away to leave a depending lug 66. The rectangular portion 62 of the check valve may thus be longitudinally stretched so as to decrease its thickness and be insertable in the slot 68 formed between the lug 66 and the main body 10. Upon relieving the tension 40 on the rectangular portion 62 it will wedge itself within the slot 68 with its circular portion overlying the end of the duct 58.

The body 10 has a plurality of openings 70 formed in the lower end thereof, the height of these openings being greater than the thickness of the piston 22.

The device is operable in the following manner: The ink well 38 is partially filled with ink to a level slightly above the check valves 60 so as to permit sufficient space for the ink, the level of which in the ink well is raised upon operation of the device. A fountain pen, for example, of the self-filling sac type, is then inserted in the obturator tube 24, as indicated in Fig. 2, with the outer lower edge of the pen section 72 engaging the frusto-conical surface 30 of the obturator tube. As previously stated, the obturator tube is made sufficiently soft (of rubber or similar material) that sealing contact with

the pen will take place upon the exertion of a slight downward pressure upon the pen.

The pen is then moved downwardly against the force of the spring 32. Downward movement of the stem assembly causes a partial vacuum to form within the cylindrical bore 12 above the piston 22. Atmospheric pressure exerted upon the outer surface of the rubber sac in the fountain pen thus forces the air within the rubber sac downwardly through the passageways 34 and 36 into the partially evacuated space above the piston 22. The displacement of the piston 22 is much greater than the volume of the ink reservoir in the pen so that, as the piston reaches the lower end of its stroke and just prior to the position in which the openings 70 are uncovered, the pressure above the piston will be considerably below atmospheric pressure. It will be understood, of course, that the check valves 60 prevent admission of ink or air to the cylindrical bore 12 above the piston 22. When, however, the piston uncovers the openings 70, the ink within the ink well will be forced into the cylindrical bore under atmospheric pressure and into the passageways 36 and 34 and hence into the reservoir of the fountain pen (due to the tendency of the sac in the fountain pen to assume its initial tubular shape).

Upon relieving the pressure manually applied to the fountain pen the spring 32 will return the parts to normal position, as shown in Fig. 1. During this operation the ink and air within the cylindrical bore 12 will be forced outwardly past the upper surface of the check valves 60 into the ink well 38 and the parts will thus again be in condition for operation. Upon the initial downward movement of the stem and piston assembly the ring 28 uncovers the end of the passageway 50, permitting the interior of the ink well to remain at atmospheric pressure. If, through improper fitting or wear, the seal around the stem 20 should be imperfect and permit leakage of ink from the lower cylindrical bore 12 into the cylindrical bore 14 upon the upward stroke of the piston such ink will collect at the lower end of the bore 14 and be forced out of this bore upon the next operation of the device since the ring 28 has a close sliding fit in the bore 14 and acts as a piston and, by compressing the air in the chamber 14, may act to force any ink in this chamber outwardly through the passageway 52.

If desired, the lower surface of the wall 16 and the upper surface of the piston 22 may be so conformed that when the piston is in normal position there will be a space between the wall and the piston. This space will normally be filled with ink. Just prior to the completion of the downward stroke the ducts 36 will contain ink so that as soon as the port openings 70 are uncovered by the piston this

ink lying within the ducts 36 will be forced upwardly into the fountain pen and thus eliminate any possibility of the rarefied air in the space above the piston 22 from rushing through the ducts 36 and pasageway 34 into the pen before the ink covers the said ducts.

It will be understood that the above operation takes place rapidly and merely by a natural movement similar to that used in inserting and withdrawing an ordinary pen in an ink well. The device may of course be used as an ordinary ink well to supply ink to an ordinary pen and may be used to fill any of the common types of fountain pens whether of the self-filling variety or not. The device is not quite as effective in filling pens of the non-self-filling type as it is with self-filling pens of the sac type but, even in filling pens of the former type, the reservoir 20 of the pen may be filled from 75% to 95% of its capacity, which is amply sufficient to warrant the use of my device for pens of this type.

It has been found that the high vacuum, resulting from the down stroke of the piston, is effective in causing dislodgment of dirt and partially dried ink which sometimes clots the ducts in the feed bars of fountain pens, and which cannot always be removed by endevors to fill the pen by operation of the self-filling mechanism of the pen.

If desired, the passageways 50 and 52 may be omitted and instead of the interior of the inkwell vented directly to the atmosphere, for it has been found that if the parts are made with reasonable care and precision, ink will not leak past the piston stem 20.

The inkwell may be refilled easily by pouring the ink into the pen point receiving opening in the piston stem. Evaporation of the liquid constituents of the ink is negligible since the inkwell is entirely closed except for one or more small vent holes, and the ink thus prevented from becoming thick or "gummy". The inkwell can for this same reason be tipped upon its side or even inverted without spilling its contents.

While I have illustrated a preferred embodiment of my invention, many modifications may be made without departing from the spirit of my invention, and I do not wish to be limited to the precise details of construction set forth, but desire to avail myself of all changes within the scope of the appended claims. Having thus described my invention, what I claim is new and desire to secure by Letters Patent of the United States is:

1. In a filling device for fountain pens, the combination of an ink container, and means associated with said container for making a sealed connection with a fountain pen, exhausting air from the reservoir of said pen and subsequently admitting ink from said container to the reservoir of said pen, said

means being operable by a single longitudinal movement of said fountain pen.

2. In a device for filling fountain pens, the combination of a source of supply of ink, a chamber associated therewith, and means operated by a single movement of a fountain pen to create a partial vacuum in said chamber and thereafter connect said source of supply with said chamber.

3. In a device of the class described, the combination of a body having cylinders formed in the opposite ends thereof, a piston reciprocable in the lower one of said cylinders, a stem for said piston projecting into the upper one of said cylinders, said stem having a longitudinal passageway and a passageway connecting the lower end of said longitudinal passageway and the said lower cylinder above said piston, a ring guided in said upper cylinder and secured to said stem, said body having a passageway leading upwardly through the wall of said body from the lower end of said upper cylinder, a check valved passageway through the upper end of the wall of said lower cylinder, and a spring compressed between said ring and the lower end of said upper cylinder tending normally to hold said ring and piston at the upper ends of their respective cylinders.

4. In a device of the class described, the combination of a body having a bore formed therein, a piston reciprocable in said bore, a stem for said piston, said stem having a passageway therein communicating with said bore above said piston, said stem extending upwardly from said piston, means for making a sealed connection between a fountain pen and said passageway, and means for moving said piston and stem in one direction.

5. In a fountain pen filling device, the combination of suction creating means, means for making a sealed connection between a fountain pen reservoir and said suction creating means, and means for operating said suction creating means, said suction creating means including automatically operable valve means to admit ink to said reservoir only after complete operation of said suction creating means.

6. In a device for filling a hollow body with a liquid, the combination of a liquid container, means associated with said container for making a sealed connection with a hollow body to be filled with the liquid in said container, and means for exhausting air from the hollow body and subsequently admitting liquid from said container to said hollow body, both of said means being operated by a single longitudinal movement of said hollow body.

7. In a device for filling fountain pens, the combination of a source of supply of ink, a chamber associated therewith, means for making a sealed connection between the reservoir of a fountain pen and said chamber,

and means operable upon a single movement of a fountain pen into said device to expand said chamber thereby to create a partial vacuum therein and thereafter connect said source of supply with said chamber.

8. In a device for supplying liquid to a hollow body, the combination of a liquid container, means movable downwardly relative to said container for making a sealed connection with said hollow body, and means operable upon moving said body in the direction required to make said sealed connection to exhaust air from said hollow body, said last named means operating to open a passageway for the flow of the liquid from said container to said hollow body after the air has been exhausted therefrom.

9. In a device for filling hollow bodies, the combination of a source of supply of liquid, an expandible chamber, means operated by movement of the hollow body to expand said chamber, and means to connect the hollow body with said chamber whereby expansion of said chamber will partly exhaust the contents of said hollow body, said device having means to connect said hollow body to said source of supply after said hollow body has been partially exhausted whereby said liquid may flow from said source of supply to said hollow body.

10. A fountain pen filling device comprising a body having a chamber, a movable wall in said chamber, a member for moving said wall, said member having a passageway associated therewith, one end thereof communicating with said chamber, means on said member for making a sealed connection between the reservoir of the fountain pen to be filled and the other end of said passageway, said chamber having a port to admit ink to said chamber when said movable wall is moved to a predetermined position, and a check valved outlet in said body leading from said chamber to permit free flow therefrom.

11. A fountain pen filling device comprising a source of ink supply, sealing means for making an air-tight seal with the pen end of a fountain pen when the latter is moved axially against said means, and means exterior of said pen for producing a partial vacuum in the fountain pen reservoir, said last named means being operable by pressure of the fountain pen against said sealing means, and having means to admit ink to the fountain pen reservoir from said source after the partial vacuum has been produced therein.

12. In combination, a body having a bore therein, said bore having an inlet port adjacent its lower end and an outlet port adjacent its upper end, an outwardly opening check valve normally closing said outlet port, a piston in said bore, a stem connected to said piston and having a longitudinal passageway communicating with said bore above

said piston, and apertured sealing means carried by the upper end of said stem.

13. In a device of the class described, the combination of a liquid container, an expandible chamber associated therewith, means to expand said chamber thereby to create a partial vacuum therein, and means to form a sealed connection between said chamber and a hollow body to be filled with liquid from said container, said expanding means having a part forming a valve to admit liquid to said chamber from said container.

14. In combination, a body having a bore therein, said bore having an inlet port adjacent its lower end and an outlet port adjacent its upper end, an outwardly opening check valve normally closing said outlet port, a piston in said bore, a stem connected to said piston and having a longitudinal passageway communicating with said bore above said piston, apertured sealing means carried by the upper end of said stem, and resilient means to move said piston and stem upwardly.

15. In a device of the class described, the combination of a liquid container, an expandible chamber associated therewith, means to expand said chamber thereby to create a partial vacuum therein, means to form a sealed connection between said chamber and a hollow body to be filled with liquid from said container, said chamber having a normally closed passageway to admit liquid to said chamber from said container, said passageway being openable by said chamber expanding means, and resilient means normally to maintain said chamber in non-expanded condition.

16. In a device for supplying liquid to a hollow body, the combination of a liquid container, means movable relative to said container for making a sealed connection with said hollow body, and means deriving its power from and operated by movement of said body in the direction required to make said sealed connection to exhaust said hollow body and thereafter open a passageway for the flow of liquid from said container to said hollow body.

17. In a device of the class described, the combination of a body member having a bore therein, a piston reciprocable in said bore, a piston stem guided in said body, said stem having a passageway leading to the juncture of said stem and piston, and resilient means for moving said piston and stem in one direction, said body having a check valved passageway leading from the upper end of said bore to the outer surface of said body and permitting flow from the bore but preventing flow in the reverse direction.

18. In combination, a body having its lower end immersed in a liquid and having a chamber associated therewith, said chamber having an inlet port adjacent its lower end

- and an outlet port adjacent its upper end, an outwardly opening check valve normally closing said outlet port, a member reciprocable in said chamber, a stem for said member having a longitudinal passageway communicating with said chamber above said member, and sealing means carried by said stem.
19. In a device of the class described, the combination of a liquid container, an expandable chamber associated therewith, said chamber having a check valved outlet, means to expand said chamber thereby to create a partial vacuum therein, and means to form a sealed connection between a hollow body and said chamber, said chamber having valve means to admit liquid thereto from said container when the former has been expanded to substantially its maximum limit.
20. In a device of the class described, the combination of an ink reservoir, a chamber having a movable wall associated therewith for expanding said chamber and creating a partial vacuum therein, a member operatively connected with said wall, means on said member to make a sealed connection between said chamber and a fountain pen to be filled when the latter is pressed thereagainst to operate said member, said chamber having a passageway to permit flow of ink to said chamber when said movable wall is in a predetermined position and to prevent such flow when said wall is in a different position.
21. In a device for filling fountain pens, the combination of a source of supply of ink, cooperative relatively movable elements forming an expandable chamber, a member having sealing means for making an air tight connection with the end of the barrel of a fountain pen, said member having a passageway in communication with said chamber, one of said elements preventing flow of ink from said source to said chamber except when said chamber is fully expanded.
22. In a device for filling fountain pens, the combination of an ink container, a hollow member having a port in its lower end immersed in the ink in said container and having an outlet passageway adjacent its upper end, an outwardly opening check valve for closing said passageway, and a reciprocable piston in said hollow member, said piston having means for making a sealed connection with the barrel of a fountain pen and a passageway from said means to said hollow member above said piston, said piston being adapted to uncover said port at the lower end of its stroke.
23. In a device for filling fountain pens, the combination of a source of supply of ink, a chamber associated therewith, and means operative by movement of a fountain pen to create a partial vacuum in said chamber and thereafter to connect said source of supply with said chamber.
24. In an apparatus for filling fountain
- pens, the combination of an ink container, means associated with said container for making a sealed connection with the reservoir of a fountain pen to be filled from said container, and means for exhausting the contents of the reservoir of said fountain pen and thereafter admitting liquid from said container to said fountain pen reservoir, both of said means being operated by movement of the fountain pen relative to said container.
- In witness whereof, I hereunto subscribe my name this 8 day of May, 1930.
- OWEN R. TERRY.
